UNITED STATES PATENT OFFICE.

GEORGE L. RICKS, OF TULIA, TEXAS.

FENCE.

SPECIFICATION forming part of Letters Patent No. 764,378, dated July 5, 1904.

Application filed October 3, 1903, Serial No. 175,668. (No model.)

To all whom it may concern:

Be it known that I, GEORGE L. RICKS, a citizen of the United States, residing at Tulia, in the county of Swisher and State of Texas, 5 have invented new and useful Improvements in Fences, of which the following is a specification.

My invention relates to fences, more particularly to the posts and stays used in the 10 construction thereof; and its primary object is to provide new and useful fence posts and stays which are cheap, durable, and efficient.

A further object of the invention is to provide a corner-post with means to clamp the 15 wires of a fence in taut position to prevent their slackening.

Still further objects of the invention will appear as the nature of the same is more fully understood from the following description and 20 accompanying drawings, which disclose the preferred form of my invention.

The invention consists in the construction, combination, and arrangement of parts hereinafter fully described, claimed, and illustrated in the accompanying drawings, in which—

Figure 1 is a perspective view of a fence constructed in accordance with my invention. Fig. 2 is a side elevation thereof. Fig. 3 is a 25 perspective view of one of the intermediate posts of the fence. Fig. 4 is a vertical longitudinal sectional view of one of the corner-posts. Fig. 5 is a similar view of one of the stays. Fig. 6 is a detail perspective view of 30 a fragmentary portion of one of the corner-posts, the same illustrating the means for clamping the horizontal wires in their taut position.

Referring to the drawings by reference- 40 numerals, 1 designates a fence-post preferably U-shaped in cross-section and slightly tapered toward its upper end. The post has one of its flanges, 2, provided with L-shaped slots 3, while its other flange, 2^a, is provided with 45 inverted-L-shaped slots 4. These slots are arranged on the flanges 2 and 2^a in staggered relation to dispose the entrances to the slots 4 at points below the entrances to the slots 3 to prevent the wires from becoming 50 accidentally disengaged from the slots in a

manner that is obvious. The flanges 2 and 2^a have their lower ends provided with depending nibs 5, adapted to be passed through slots 6 in a base-plate 7. After the nibs 5 have passed through said slots they are bent to engage the under surface of the base-plate that the same may be clamped between the lower ends of the flanges and themselves, whereby it is firmly secured in applied position. 55

The post above described is especially adapted for use as an intermediate post, while the corner-post, which is of a similar construction, is provided with means for holding the longitudinal wires of a fence taut. This means consists of inverted-L-shaped brackets 8, secured one above the other on the connecting-flange 9 of the post and in the corners thereof to dispose their horizontal portions in alignment with the lower and upper extremities of the slots 3 and 4, respectively. Pivotedly secured upon flange 9 above the horizontal portions of the brackets 8 are levers 10, having cam-shaped heads 11, adapted to engage the horizontal wires of a fence and clamp them against the horizontal portions of the brackets 8. The under faces of the cam-heads are provided with corrugations adapted to engage the horizontal wires when the levers 10 are swung to prevent the wires from slipping between the brackets and cams. It is apparent when the cam-heads are caused to engage the horizontal wires of a fence that said wires are securely held in taut position, as from the construction of the cam-heads any longitudinal reverse strain on the horizontal wires will 75 cause said heads to secure and more firmly clamp the wires against the brackets 8. 80

The corner-posts are provided with stay-wires 12, each having one of its ends secured to the post, while its opposite end is secured 90 to an anchor 13, firmly driven into the ground. These stays are provided for the purpose of preventing the posts from becoming loose in their applied positions. The stays 14 are U-shaped in cross-section, and each has a flange 95 15 thereof provided with L-shaped slots 16 and its flange 17 provided with inverted-L-shaped slots 18. The lower walls of the vertical portions of the slots 16 are situated at points above the upper walls of the vertical 100

portions of the slots 17 in order that when the stays are secured upon the horizontal wires of the fence the wires are caused to assume a crimped position, as disclosed in Fig. 2 of the 5 drawings, to effectively retain the stays in their applied position.

The application of the horizontal wires of a fence to the posts 1 may be described in the following manner: The wires are first inserted in 10 the horizontal portions of the slots 3 and then into the vertical portions thereof, after which they are inserted into the horizontal portions of the slots 4, after which they are brought into 15 the vertical portions thereof, which crimped condition will prevent the wires from becoming accidentally disengaged from the slots and also assist in holding the wires taut. The stays 16 are applied to the horizontal wires in a similar manner, and the crimping of the 20 wires thereby will retain them in applied position thereon. After the wires are stretched the levers 10 may be swung to clamp the wires against the horizontal portions of the brackets 8 to securely retain them in their taut positions. 25

Having thus described the invention, what is claimed as new is—

1. In a fence, the combination of a **U**-shaped fence-post having **L**-shaped slots arranged in 30 its flanges in staggered relation, wires adapted

to be received by said slots, brackets secured to the connecting-flange of the post, said brackets being arranged in series and positioned to dispose one series in alinement with the upper extremities of the vertical portions 35 of the slots in one flange and the other series in alinement with the lower extremities of the vertical portions of the slots in the other flange, and cams pivotally secured above the brackets. 40

2. In a fence, the combination of a **U**-shaped fence-post having **L**-shaped slots arranged in its flanges in staggered relation, wires adapted to be received by said slots, **L**-shaped brackets secured to the connecting-flange of the post, 45 said brackets being arranged in series and positioned to dispose the horizontal members of the brackets of one series in alinement with the upper extremities of the vertical portions of the slots in one flange and the horizontal members of the other series in alinement with the lower extremities of the vertical portions 50 of the slots in the other flange, and cams pivotally secured above said brackets.

In testimony whereof I affix my signature in 55 presence of two witnesses.

GEO. L. RICKS.
